COMBINED SUPPORT AND PICKLING RACK

Application filed October 10, 1929. Serial No. 392,640.

This invention as indicated relates to a combined support and pickling rack. More particularly it comprises a handling device for hot plates which is adapted to receive the plates in a horizontal position and to suitably hold them when the device is turned to vertical position so that the usual pickling operation may be carried through.

It is the present practice to carry the plates from the rolls to a pile and thereafter to insert plates from said pile into a cage or rack, the plates being set on edge between stakes and suitable supporters being employed upon each of the plates to permit the pickling fluid to flow freely upon the plates. The pickling cage is ordinarily handled by means of four chains or cables connected with the crane which then reciprocates the cage vertically within the pickling vat for the necessary period of time and thereafter in a rinsing vat after which the plates are returned to the rolls for the final finishing treatment. The carrying of the plates from the rolls to the table from which they are inserted in the pickling rack and after the pickling operation reversing the process involves a double handling of all of this material and ordinarily requires the employment of some six laborers. With the present device, the pickling cage itself receives the plates in a horizontal position as they are carried directly from the rolls and the operation of handling the plates may be easily carried out by two laborers. Thus there is a saving in labor cost and in time, and the pickling operation can be carried through with sufficient speed to prevent the delays which frequently are experienced at the finishing rolls. To the accomplishment of the foregoing and related ends, said invention, then, consists of the means hereinafter fully described and particularly pointed out in the claims.

The annexed drawings and the following description set forth in detail certain means and one mode of carrying out the invention, such disclosed means and mode illustrating, however, but one of various ways in which the principle of the invention may be used.

In said annexed drawings:—
50 Fig. 1 is an end elevation, partly in section,

of a combined support and pickling rack in position to receive the plates; Fig. 2 is a plan view of the bottom frame member of the device; Fig. 3 is a side elevation of the device showing the rigid yoke member; Fig. 4 is a side elevation of the pivoted yoke member; Fig. 5 is an end view of the cage with the yokes in supporting position and the top cross bar engaged with the upper ends thereof; Fig. 6 is a perspective view, broken away in part, showing a modified form of construction; and Fig. 7 is an end elevation, partly in section, of the apparatus shown in Fig. 6.

As is clearly shown in the drawings, the pickling rack comprises a base member 1 in the form of an open frame having a rectangular outline with the flanged members 2 extending continuously about the same and having a plurality of cross members, 3, 4, 5, of T-shaped cross-section. Three cross members are shown in the device illustrated and the two outer cross-members, 3, 5, are formed with bosses or enlargements 6 and are provided with sockets 7 therein adapted to receive the spacing stakes 8. At the points where the two outer cross members extend across the frame, enlargements 9, 10, are formed, the enlargements 9 at one side having sockets 11, to receive the ends of the fixed yoke member 12 formed with suitable shoulders to abut the upper sides thereof and having threaded ends 13 upon which securing nuts 14 are engaged. The yoke members each comprise parallel arms 15 joined at their upper ends by inclined members 16. At the apex of the inclined members in the fixed yoke, a pair of upstanding ears 17 are provided through which a pivot pin 18 is engaged. The movable yoke member 19 is of similar outline and is provided with eyes 21 at the ends of its parallel arms 22, which eyes engage in slots 23 formed in the enlargements 10 of the frame member opposite the two outer cross-members, and pivot pins 24 serve to connect the same with said bosses or enlargements in said frame member to permit said yoke to be moved to a position parallel with the fixed yoke member as is shown in Fig. 5 or to a position rearwardly of the base member and inclined thereto so as to serve as a support

for the rack when the plates are to be deposited on or removed therefrom. The upper end of the movable yoke has inclined arms 25 at the apex of which an apertured extension 26 is provided adapted to receive the free end of the cross-bar 20 which is pivoted at its opposite end to the fixed yoke. The cross-bar preferably is formed with a straight lower edge and an arcuate upper edge so as to give greater strength centrally of the same and is provided with an enlarged aperture 27 centrally to provide for engagement of a hoisting hook or like attachment. The free end of the cross-bar is provided with some suitable fastening means whereby it may be firmly engaged with the movable yoke. In the drawings such securing means comprises a transverse aperture 28 through the end of the cross-bar through which a suitable anchoring pin 29 or other fastening element may be engaged.

The method of using the device has already been disclosed in part. The preferred manner of using the same comprises turning the rack so that the fixed yoke will rest upon the floor or other supporting surface with the base member in a vertical position and with the movable yoke extending rearwardly of the rack at an angle to the base member and serving as a prop for the same. The cross-bar is moved outwardly from the top of the fixed yoke as is shown in Fig. 1 and provides no obstruction to the ready deposit of the hot plates upon the fixed yoke.

35 The plates are piled on the yoke in the manner shown in Fig. 1 and when a sufficient quantity of plates has been accumulated to reach the level of the lower stake holes shown, stakes are inserted in the base and a second series of plates is then piled above such stakes until the level of the second pair of stake holes is reached. When the second set of stakes is inserted, further plates are piled upon the device until the level of the pivot at the top of the base member is reached. The movable yoke is then swung to horizontal position parallel to the fixed yoke, the cross-bar being engaged with the aperture at the top of the movable yoke and being securely anchored in position. The hoisting attachment is then connected with the cross-bar and the frame is turned to vertical position. Spacing clips may be applied to the plates when they are first placed within the pickling rack or such clips may be applied at the upper edge of the plates after the pickling rack has been turned to vertical position with the plates on edge. Chains 31 are fastened around the end portions of the plates, being secured to suitable eye bolts 32 positioned at a central point of the yoke members at either side.

60 In the form of construction illustrated in Figs. 6 and 7, the general frame and fixed and movable yoke members are the same as

those first described, excepting that only two cross-members 33, 34, are illustrated and these being relatively heavy and of square cross-section. The equalizing stakes or posts are replaced by a series of very small stakes 70 35 permanently secured to the outer cross-members by means of sockets and clamping nuts 36, the upper ends 37 of such stakes being beveled. These fixed stakes or equalizing members are positioned at predetermined points according to the number of sheets to be held in one lot which differ according to the character of the material to be pickled and may for example contain fifteen plates in each group or twenty or thirty 80 or any other number found most practical for the speedy operation of the pickling bath. It will be noted from the drawings that the fixed equalizing members separate the layers at the base of the frame. In order to support the free edges of the plates a built-up 85 equalizing member 38 is provided. This built-up member is adapted to be supported upon supporting bars 41, 42, which are engaged at their ends with the respective side frame members and are slidable upon the lateral arms of said side frame members. In handling break down plates but one equalizing member need be provided, while with longer finishing plates it may be necessary 90 to provide two or more series of equalizing members.

95 In the form of construction illustrated each of the side frame members has a sliding supporting bar engaged over its lateral arms. The supporting bar 41 on the fixed side frame member carries at a central point the base equalizing unit 43 of the built-up 100 series which is provided with a socket 44 to receive the cooperating member which may be in the form of a dowel pin upon the next member to be secured thereto. The second member carries, in the form illustrated, a dowel pin and the second unit comprises a tapered spacing member 46 and a body portion 47 at right angles thereto. The body portion carries a dowel pin 48 and is adapted to cooperate with the socket 44 in the base member body portion. On the upper side of the spacing member a socket 49 is provided with which a dowel pin 50 of another unit 51 is adapted to be engaged. The last named unit preferably is provided with a larger body section than that first described, inasmuch as it fits into the adjacent member 105 immediately above the tapered spacing portion and not into the body of the base member as the first unit described. All succeeding units are preferably of the form last described as to the height of the body member and the taper of the spacing members, excepting the upper section 52, which need not be provided with a taper on its projecting member and which preferably is provided with a slot 53 to receive the cross bar, 110 115 120 125 130

which is slidably carried upon the pivoted side member.

Thus by building up the several units in the manner described, the plates may be spaced at their free edges to correspond with the spacing provided on the base member by the projecting equalizing members engaged through the outer cross-bars.

The operation of the device is similar to 10 that heretofore described, but has this advantage over the former construction wherein stakes are used in that a chain may be placed around the entire series of plates prior to the withdrawal of the equalizer members 15 from the front edges thereof and after the chain is so disposed above the plates the equalizing members at the front edges of such plates may be withdrawn simultaneously from the whole series of plates and the 20 plates lifted bodily from the rack without the loss of time which would be involved in withdrawing the stakes in the form of construction shown in Fig. 1.

With the apparatus described it is possible 25 to carry plates directly from the rolls to the pickling rack and pile them in position for the pickling operation at once without any rehandling. This avoids the necessity 30 of having an extra number of laborers because of the intense heat experienced where the laborers stand between two piles of hot plates as is now generally necessary under the present practice. It also permits the 35 transfer of what are known as the "break-down" plates from the rolls to the pickling vats in a minimum of time. After the pickling operation is completed the process of transferring the plates to the finishing rolls is merely a reversal of that heretofore 40 described, the pickling rack being turned on its side and the cross member and movable yoke being turned to the position shown in Fig. 1 and the plates then being removed for handling at the finishing rolls. Through 45 the use of the apparatus set forth, the pickling operation can be carried through in a limited time which will correspond to the other operations at a plant and not result in the delay of highly paid labor at the rolls 50 through the slowness with which the unskilled labor ordinarily operates in connection with the pickling process.

Other modes of applying the principle of my invention may be employed instead of the 55 one explained, change being made as regards the means and the steps herein disclosed, provided those stated by any of the following claims or their equivalent be employed.

I therefore particularly point out and distinctly claim as my invention:—

1. An apparatus of the character described having in combination a frame comprising a base, a side member rigidly secured to one side of said base, a side member hingedly secured to the other side of said base opposite

said rigid side member, and means adapted to be connected to the free end of said side members for handling the same.

2. A device of the character described having in combination an open frame base, a plurality of cross members extending across said frame, a rigid side member secured to said frame adjacent said outer cross members, a pivoted side member connected to said frame at the opposite end of said outer cross members, and means for connecting the free ends of said side members for handling said frame. 70

3. A device of the character described having in combination an open frame base, a plurality of cross members extending across said frame, a rigid side member secured to said frame adjacent said outer cross members, a pivoted side member connected to said frame at the opposite end of said outer cross members, combined supporting and spacing stakes 80 85 removably supported at intermediate points in said outer cross members and serving for said respective functions when the frame is positioned—first horizontally, and thereafter vertically, and means for connecting the free ends of said side members for handling said frame. 90

4. An apparatus of the character described having in combination a pickling rack comprising a base, a yoke rigidly secured to one side of said base at right angles thereto, a corresponding yoke pivotally secured to the opposite side of said base and adapted to be turned to parallel position with said rigid yoke or rearwardly of said base to act as a support. 95 100

5. An apparatus of the character described having in combination a pickling rack comprising a base, a yoke rigidly secured to one side of said base at right angles thereto, a corresponding yoke pivotally secured to the opposite side of said base and adapted to be turned into parallel position with said rigid yoke, means for connecting the free ends of said side members and rigidly holding the same in parallel relation, and means slidably supported upon said yokes when turned to parallel position for spacing the plates supported within said rack. 105 110

6. An apparatus of the character described having in combination a pickling rack comprising a base, a plurality of fixed, combined spacing and supporting members mounted on said base and engaging plates within the rack adjacent one edge thereof, a yoke rigidly secured to one side of said base at right angles thereto, a corresponding yoke pivotally secured to the opposite side of said base and adapted to be turned into parallel position with said rigid yoke, means for connecting the free ends of said side members and rigidly holding a plurality of the same in parallel relation, and combined spacing and supporting members slidably supported upon said yokes when turned to parallel position 115 120 125 130

for spacing and supporting the opposite edges of the plates positioned within said rack.

7. An apparatus of the character described having in combination a pickling rack comprising a base, a plurality of spacing members mounted on said base, a yoke rigidly secured to one side of said base at right angles thereto, a corresponding yoke pivotally secured to the opposite side of said base and adapted to be turned into parallel position with said rigid yoke, means for connecting the free ends of said side members and rigidly holding the same in parallel relation, supporting bars slidably supported upon said yokes when turned to parallel position, and a series of interlocking spacing units adapted to be supported upon said supporting bars for spacing the plates supported within said rack.

8. An apparatus of the character described having in combination a pickling rack comprising a base, a plurality of spacing members mounted on said base, a yoke rigidly secured to one side of said base at right angles thereto, a corresponding yoke pivotally secured to the opposite side of said base and adapted to be turned into parallel position with said rigid yoke, means for connecting the free ends of said side members and rigidly holding the same in parallel relation, supporting bars slidably supported upon said yokes when turned to parallel position, and a series of interlocking spacing units having pin and socket connection with each other adapted to be supported upon said supporting bars for spacing the plates supported within said rack.

Signed by me this 5th day of September, 1929.

GRANT U. HILLIARD.
